Primary Examiner — Jonathan J Han(74) Attorney, Agent, or Firm — Schwabe, Williamson & Wyatt, P.C.(57) CLAIM

I claim the ornamental design for a shoe, as shown and described.

DESCRIPTION

FIG. 1 is a front perspective view of a shoe, showing my new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a front perspective view thereof, showing the free end of the strap away from the shoe.

The dot-dash broken lines adjacent to the shaded areas represent boundaries of the claimed design and form no part thereof. The remainder of the broken lines show portions of the shoe that form no part of the claimed design.
